UNITED STATES PATENT OFFICE.

JESSE A. B. SMITH, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,149,794.

Specification of Letters Patent. Patented Aug. 10, 1915.

Application filed May 27, 1914. Serial No. 841,184.

To all whom it may concern:

Be it known that I, JESSE A. B. SMITH, a citizen of the United States, residing in Brooklyn borough, in the county of Kings, 5 city and State of New York, have invented certain new and useful Improvements in Type-Writing Machines, of which the following is a specification.

This invention relates to sheet-collating devices for typewriting machines, and is directed toward the general construction and arrangement of such devices as shown in Patent No. 1,107,372, granted August 18, 1914.

15 One of the objects of the present invention is to provide an improved form of collating board or frame having sheet-carrying devices and upon which the sheets to receive writing may be assembled while said board lies in a forward position, to which it is capable of adjustment. In such position, the collating board extends about horizontally toward the operator, thereby permitting the operator to readily and conveniently 20 adjust the sheets. This advantage is gained by means of the provision of an angle in the collating board, which allows the lower portion thereof (which may be mounted on the platen axle) to extend at an upward and forward inclination for a sufficient distance, so that when swung forwardly the board 25 will clear the top front bar of the machine, thereby permitting the upper portion of said board to lie in the desired horizontal plane. 30 A further purpose served by the provision of the angle, is that the consequent forward inclination of the lower portion of said collating board (when upstanding) presents the sheets in a more direct introductory 35 manner to the platen.

The sheet-carrying devices which consist of endless bands having studs to enter apertures therefor in the sheet margins, also have apertures by which they may engage 45 with teeth arranged upon cylindrical caps disposed one at each end of the platen, and also with teeth upon pulleys mounted in bearings at each end of the upper portion of the collating board, to divide the carrying 50 strain for each band between the platen and said pulleys, and to dispense with lateral guides for preventing the bands from slipping off the pulleys.

The toothed, cylindrical caps may fit over 55 recessed portions at the platen ends in order

that they may lie flush with the platen surface. The pulley bearings at the upper end of the collating-board may consist of flat strips having their opposite ends bent upwardly at right angles to the base portion 60 and provided with alined bearings to receive the pulley shaft, these strips being supported on rods which are mounted upon springs in brackets provided at the opposite upper corners of said collating-board, the 65 springs providing a flexible support for the pulleys to take up the slack in said endless bands. The bent ends or walls of the said strips have rounded upper edges to receive the ends of an outer curved guide plate, 70 which is adapted to fit over and cover the entire upper length of the collating-board, including the pulleys and which also covers an inner curved guide plate that extends between the pulleys, there being a clearance 75 between said outer and inner guide plates for the passage of the work-sheets. The outer guide plate has transverse enlargements at its opposite ends to provide clearance spaces for the passage therethrough of 80 the projecting studs upon the endless bands, and means of connection between said outer guide plate and said pulley-supporting members or strips are provided whereby said outer guide plate may be secured in position. 85 The forward lip of the outer guide plate flares forwardly to facilitate entry of work-sheets and the adjacent edge of the inner guide plate flares rearwardly for a similar purpose. A finger extends downwardly and 90 rearwardly from said inner guide plate to prevent the center of the work-sheet being carried upwardly from sagging and for directing the leading edge of said work-sheet between the lips of the outer and inner 95 guides. The side edges of the collating-board are provided with guide strips for the endless bands, said guide strips extending over the outer edges respectively of said bands, and said guide strips may be pro- 100 vided each with a scale whose graduations bear numbers whereby may be designated the position of a desired writing line in assembling the work-sheets.

Means for supporting the collating-board 105 when brought to the horizontal position for assembling sheets thereon consist of brackets having curved upper surfaces mounted upon the front bar of the platen frame, which forms part of the usual carriage, to 110

be movable therewith, said brackets being in position respectively to engage the endless bands, which latter, under the weight of the collating-board which they carry, yield to the curvature of said bracket-supporting surfaces, said brackets having grooves or recesses to receive the paper engaging studs on the bands in order that even contact may occur between the bands and brackets during the support of said bands by said brackets.

The rear plate or frame which supports the adjustable collating-board when in its operative position is securely supported in an upright position upon the forward surface of the paper table, and is provided with an inclined lower portion whose angle coincides with that of the collating-board whereby the opposed surfaces of said collating-board and the rear plate lie in parallel planes spaced apart sufficiently for the travel of the endless bands and the work-sheets they carry. The rear plate or frame has lateral lugs with bearing surfaces a little in advance of the front surface of said plate adapted to engage bearing surfaces on the collating-board whereby said collating-board is supported in the desired relative position upon said rear plate or frame.

In order that the collating-board when drawn forwardly to horizontal position may be held in that position against the tension of the springs which are retracted by the endless bands yielding under the weight of said collating-board, I provide catches which may be mounted upon the platen frame at each side thereof and have cam surfaces associated therewith, the collating-board having crank arms extending from a spring held rocking-rod, journaled in lugs extending from said collating board, whereby as the collating-board is swung forwardly the crank arms ride over the cams and engage with the catches to hold the collating-board horizontally until released.

Other objects and advantages will herein-after appear.

In the accompanying drawings, Figure 1 is a perspective elevation of my improved collating-board shown as mounted upon the carriage of an Underwood typewriting machine and in operative position. Fig. 2 is a similar view, the collating-board being shown as swung forwardly to a horizontal position for assembling sheets thereon, the rear supporting plate being partly broken away and the outer guide for the collating-board shown as removed. Fig. 3 is a side elevation of the collating-board shown in operative position. Fig. 4 is an enlarged detail side sectional view showing the upper pulley, the endless band thereon and the inner and outer guides. Fig. 5 is a partial view in side elevation showing the collating-board swung forward to horizontal position,

and Fig. 6 is a side view of the line-spacing mechanism by which the endless belts are advanced together with the platen in the rotation of the latter.

The rotary platen 1 is fixed to the platen shaft 2, journaled in the ends of the platen frame 3, which latter includes the usual paper shelf or table 3a. The platen may be rotated either by the usual hand wheels 4 fixed on the ends of the shaft 2, or by line-space mechanism which may comprise a ratchet wheel 5 fixed to the platen axle and rotated by a pawl 6 pivoted at 7 to the slide 8, the latter actuated by a line-space lever 9, which also serves to return the carriage.

The throw of the pawl may be regulated as usual by a gage 10 adjustable by a hand lever 11 to vary the point at which the pawl 6 is permitted to move downwardly into engagement with the ratchet wheel, and thus determine the effective throw of the pawl. The usual spring-pressed detent 12 engages the ratchet wheel to hold the platen at line-space intervals and prevents accidental movement.

The collating board 13 is here shown as having forwardly-extending brackets or lugs forming bearings 14 by which it is pivotally mounted upon the platen axle 2. Said collating board might be otherwise mounted, but it is manifestly convenient to provide a common axis for both the platen and collating board in view of the fact that said collating board is intended to swing over the platen from an upright operative position, shown in Fig. 1, to a horizontal position, shown in Fig. 2, in which latter position it is adapted to receive the different work-sheets for which it is intended.

The collating board may be of suitable construction and material, and as here shown it consists of a light frame in the form of an aluminum casting having intersecting bars with open panels, thus possessing the desired degree of rigidity and strength, and of light weight. The collating board or frame at its junction with the lugs or brackets 14 is offset with relation to its axis, and from that junction it extends to a point 15 at an angle which, in the operative position, gives it a rearward inclination relatively to the main forward portion of said board, which rises nearly vertically therefrom, or with only a slight rearward inclination. The rearward inclination of the lower portion of the collating board allows its upper portion, when swung forwardly over the platen and front portion of the machine frame, to be presented in such manner as to lie horizontally before the operator.

Mounted in brackets 16 upon springs 17 arranged near each upper end of the collating board are rods 18 which thus yieldingly

support a bearing strip or frame comprising a base 19 to which said rods are secured, and upwardly extended end walls 20, having aligned orifices 21 forming bearings for 5 pivots 22 which carry the pulleys 23. Said pulleys are provided with peripheral teeth 24 which cooperate with teeth 25 upon the cylindrical caps 26 fitted on the platen ends to carry endless belts 27 which have orifices 10 28 arranged in a line to feed over said pulleys and platen ends by means of said peripheral teeth.

The cylindrical caps for the platen ends may have hubs 29 whereby said caps serve 15 the purpose of the usual platen end plates, the cylindrical or pulley portion of said caps having a diameter equal to that of the platen, which latter is annularly recessed to receive said caps and allow their cylindrical surfaces to lie flush with the cylindrical surface of the platen. The endless bands 27 each carry in an endless line a row 20 of studs 30 spaced apart in accordance with the spacing between the apertures in the work-sheets to be carried by said bands, the 25 studs 30 engaging said work-sheet apertures to advance said work-sheets with the travel of said bands, and said bands advancing with the step-by-step line-spacing 30 rotation of the platen, or with the platen as otherwise rotated.

The collating board is supported, when in its upright operative position, by means of a rear plate or frame 31, which may be of 35 similar character to the collating board in its structure, and is illustrated as of such construction, being composed of intersecting bars with open spaces or panels for the sake of strength and rigidity, with light 40 weight. Frame 31 is provided with a smooth front surface plate or sheet 32, which is secured thereto as by screws 33, wherefore said frame with its sheet 32, conforms in contour with the collating board 13, so that 45 the latter may lie parallel therewith, when in operative position. The collating board 13 has side lugs 34 with bearing surfaces adapted to engage laterally extending lugs or brackets 35 on the frame 31, said lateral 50 lugs lying in the path of the lugs 34 on the collating frame in order to arrest the rearward movement of said collating frame a little in advance of the surface plate 32, and thus provide an intermediate space between 55 said collating frame and plate 32, for the passage of the endless bands and the sheets they carry. By reason of the rearward angle at which the lower portions of the collating board and rear frame extend upwardly, aided by the slight rearward inclination of the main upper portions of said collating board and rear frame, the collating board when moved rearwardly to its 60 operative position, is retained in that operative position by gravity.

The front bar 36 of the platen frame has mounted thereon, near each end, a bracket consisting of a member 37 having a curved upper surface with a groove or depression 38 extending transversely thereof, said 70 curved member having legs 39 with feet 40 by which they are secured, as with screws, to said bar. The said brackets are positioned upon the frame in alinement with the endless bands 27 to engage the latter 75 when the collating board is swung down horizontally over the front part of the machine, the grooves or depressions 38 then receiving the studs 30 upon the endless belts, and said belts yielding through the compression of the springs 17 under the weight of the collating board, which they support, to conform to the contour of said brackets, and thereby allowing the collating board to be lowered to present its surface horizontally. 80 toward the operator. The work-sheet, such as ledger sheets, invoice sheet, statement, and other desired work-sheets, can be arranged in superposed relation, with interleaved carbon sheets where desired, upon the 85 collating board thus extended horizontally toward the operator, the work-sheets being assembled upon said collating board by placing their marginal orifices over the 90 studs 30 on the bands 27.

The collating board is provided on its assembling surface, at one or both sides thereof, with a guide strip 41 which lies over the outer edge portion of an adjacent endless band, and said guides may each have 100 mounted upon them, a scale plate 42 bearing numbered graduations at line space intervals apart, whereby the operator upon inserting a new work-sheet may conveniently 105 register the writing lines thereon, in accordance with lines previously written upon other work-sheets, borne by the collating board. The end walls 20 of the pulley bearing frame, which are of rounded contour at their upper portions, are thereby adapted to support an outer guide plate 43, which is of inverted trough-like configuration, with open ends to receive said walls 20, and said walls may have inturned flanges 44, front 110 and rear, to provide engaging surfaces by 115 which said trough may be conveniently detachably secured in position, as by the use of screws. The guide plate 43, which thus extends over the entire upper portion of the collating board, including the endless bands, 120 is spaced apart from said endless bands to provide sufficient clearance for the passage of the work-sheets carried by said endless bands, which are thus passed upwardly 125 around the inner surface of said guide plate to descend at the rear surface of the collating board between it and the surface plate 32 of the rear frame 31.

The outer guide plate 43 aforesaid has transversely expanded enlargements 44^a 130

lying over that portion of each endless band carrying the studs 30, to provide clearance spaces for the passage of the studs, these enlargements 44^a being desirable because by 5 their use it becomes unnecessary to unduly increase the clearance provided by said guide for the work-sheets, their use further enabling said guide plate to be compact in area.

10 The forward edge or lip 45 of the guide plate 43 is outwardly flared to facilitate entry of work-sheets. An inner guide plate 46 is also provided, this guide plate 46 extending over the longitudinal space between 15 the pulleys 23 and downwardly beyond the latter on opposite sides, and having an upper surface curved in substantial conformity with the cylindrical contour of the upper portions of the pulleys. The forward 20 extension of this guide plate 46 has an inwardly flared edge or lip 47 to coöperate with the outwardly flared edge 45 of guide 43 for the introduction to the space which is provided between the guides, of work- 25 sheets which are to pass through said space in traveling around to the rear of the collating board.

The rear portion of the inner guide 46 extends over the upper portion of the rear 30 surface of the collating board to form a portion of the supporting surface thereof. Said inner guide may be secured in its position as noted, by means of inturned lugs 48 which extend from its forward and rear 35 portions at the sides thereof and are adapted for engagement with the inner faces of the walls 20 of the bearing frame.

It will thus be apparent that sheets assembled upon the endless bands, when advanced around the platen and up to the top of the apparatus, will by means of the outer and inner guides, be directed around the top portion of the collating board and downwardly between said collating board 45 and the rear frame, at which point, without removal of said assembled sheets, or with removal of some of them, other sheets may be assembled on top of said sheets for a second passage around the platen.

50 To prevent the sheets ascending in front of the machine from sagging at the center, between the two endless bands and thereby failing to freely enter the space between the guides, a guide finger 49 is attached to the lip or edge 47 of the inner guide, said finger extending downwardly and inwardly to the surface of the collating board, to which it may be made fast, as seen, thereby serving to properly direct the leading edges of work- 55 sheets which may sag centrally, to the entrance at lips 45, 47, between the guide plates.

60 It will be seen that the weight of the collating board and the rearward inclination 65 it assumes in its operative position serve

to sustain said collating board in that position. When said collating board is swung forwardly for the purpose of assembling sheets thereon, the forward spans of the endless bands then come to rest upon the 70 brackets 37 with whose curved surfaces they contact, the weight of the structure thus supported serving to contract the springs 17, and causing the rods 18 to slide within the brackets 16 because a portion of the length 75 of the endless bands has been displaced under said weight, the sagging displacement which has thus occurred allowing said collating board to present its rear surface more nearly in a horizontal position than would 80 be possible were the endless bands unyielding and incapable of sagging in the manner described.

In order that the collating board, as thus presented to the operator, may be sustained 85 in that position while sheets are being assembled thereon, certain locking means are provided as follows. The lugs 34 upon the collating board serve as bearings for a rod 50, which is adapted to rock therein but is 90 restrained by a spring 51. Said rod at its outer ends is provided with crank arms 52, adapted in the forward swinging movement 95 of the collating board to meet and ride over cam surfaces 53 provided on brackets 54, which also have forward projections 55 forming catches under which said crank arms 52 become engaged by the action of spring 51, this latching or locking action occurring at the time when the collating board has been brought fully forward and the endless bands sagged to sufficient extent 100 to present the collating board as stated in a substantially horizontal position. In order to return the collating board to its operative position, the crank arms are released 105 by hand from the projections 55.

Variations may be resorted to within the scope of the invention, and portions of the improvements may be used without others. 110

Having thus described my invention, I claim:

1. A sheet-collating device for typewriting machines comprising a collating board adjustable from an operative upright position to a horizontal sheet-assembling position, means carried by said collating board for advancing sheets thereover, a stationary coöperating member at the rear of said collating board, and a forward support 115 therefor.

2. In a typewriting machine, the combination with a rotary platen, of a work-sheet-supporting board pivoted to swing about the platen axis, a stationary upright 120 board coöperating with the rear surface of said work-sheet-supporting board, said work-sheet-supporting board being movable away from said coöperating board to a forwardly extending position to permit work- 125 130

sheets to be assembled thereon, endless belts mounted to travel along said supporting board and to swing therewith, and means whereby work-sheets may be connected to 5 said belts.

3. The combination with a rotary platen, of a swinging frame on which work-sheets are to be assembled, an endless carrier swinging with said frame, a stationary 10 frame to coöperate with said swinging frame in the operative position of the latter, and means on said carrier for engaging work-sheets to feed them around the platen.

4. The combination with a rotary platen, 15 of a frame on which work-sheets are to be assembled, said frame pivoted to swing about the platen axis, a stationary frame to coöperate with said swinging frame in the operative position of the latter, endless carriers extending over said swinging frame 20 and around said platen, means whereby work-sheets may be attached to said carriers, and means to drive said carriers to feed the work-sheets around the platen.

5. The combination with a rotary platen, 25 of a frame on which work-sheets are to be assembled, said frame pivoted to swing about the platen axis, and rearwardly inclined for a portion of its length to enable its forward portion to lie horizontally when 30 swung over the platen, an endless carrier supported on said frame, means on said carrier by which a work-sheet may be attached thereto, and means for causing said carrier to travel with the rotation of the platen.

6. In a machine of the character specified, the combination with a rotary platen, of a frame mounted to swing about the platen axis, said frame extending longitudinally 40 from said axis at different angles, thereby to enable it to incline rearwardly and upwardly from said axis when in operative position, and to clear the platen and lie horizontally above the machine frame when 45 swung forwardly, an endless carrier supported on said frame and extending around the platen, means on said carrier by which a work-sheet may be attached thereto, and means for causing said carrier to be advanced with the rotation of the platen.

7. The combination with a rotary platen, 50 of a swinging work-sheet board normally extending upwardly and rearwardly from the platen and adapted to swing forwardly to permit work-sheets to be placed thereon, and a rear frame rigidly supported to coöperate with said swinging board in the upward operative position of the latter.

8. The combination with a rotary platen, 60 and a work-sheet-supporting board pivoted to swing about the platen axis, of endless carriers extending over said board, means whereby work-sheets may be attached to said carriers, curved guide plates secured at 65 the upper end of said board and spaced

apart for the passage of said carriers and work-sheets therebetween, and means to advance said carriers with the rotation of the platen.

9. The combination with a rotary platen, 70 and a work-sheet-supporting board pivoted to swing about the platen axis, of endless carriers extending over said board, means whereby work-sheets may be attached to said carriers, curved guide plates secured at 75 the upper end of said board and spaced apart for the passage of said carriers and work-sheets therebetween, said guide plates having opposite outwardly flaring lips for the reception of the leading edges of the 80 work-sheets, and means to advance said carriers with the rotation of the platen.

10. The combination with a rotary platen, 85 and a work-sheet-supporting board pivoted to swing about the platen axis, of endless carriers extending over said board, means whereby work-sheets may be attached to said carriers, curved outer and inner guide plates secured at the upper end of said board and spaced apart for the passage of said 90 carriers and work-sheets therebetween, and a guide finger extending forwardly and upwardly from the forward surface of the work-sheet-supporting board to the inner guide plate to engage sagging portions of 95 work-sheets and cause the same to enter between said guide plates.

11. The combination with a rotary platen, 100 of a work-sheet-supporting board pivoted to swing about the platen axis, cylindrical caps for the platen ends having radial teeth, said caps forming the bearing end plates for the platen, and endless bands carried by said board and having apertures to engage said teeth, whereby said bands are caused to be 105 driven during rotation of said platen.

12. The combination with a rotary platen, 110 of a work-sheet-supporting board pivoted to swing about the platen axis, apertured endless belts engaged with the platen ends to be rotated thereby, and pulleys supported at the free end of said board to support said endless belts, said pulleys having radial teeth to engage with the apertures in said belts to retain said belts upon said pulleys 115 while being driven from the platen.

13. The combination with a rotary platen, 120 of a work-sheet-supporting board pivoted to swing about the platen axis and having endless belts supported thereby, said belts being provided with means for engaging work-sheets and being movable with the rotation of the platen, and belt guides extending along the outer edges of said board and bearing numbered scale markings at line- 125 space intervals.

14. The combination with a rotary platen, 130 of a work-sheet-supporting board pivoted to swing about the platen axis and having endless belts supported thereby, said belts

being provided with means for engaging work-sheets and being movable with the rotation of the platen, and a belt guide extending along a side edge of said board and bearing numbered scale markings at line-space intervals.

15. The combination with a rotary platen, of a work-sheet-supporting board pivoted to swing about the platen axis, yieldingly supported pulleys at the upper portion of said board, endless belts connecting the platen ends and said pulleys, said belts having work-sheet engaging means, a platen frame, and brackets upon said frame having curved surfaces to engage the forward spans of said belts and thereby support the board when the latter is swung forwardly to a horizontal position, said belts yielding with the yield of said pulleys under the weight of said board to allow the latter to assume a substantially horizontal position.

16. The combination with a rotary platen, of a work-sheet-supporting board pivoted to swing about the platen axis, yieldingly supported pulleys at the upper portion of said board, endless belts connecting the platen ends and said pulleys, said belts having work-sheet engaging means, a platen frame, and brackets upon said frame having curved surfaces to engage the forward spans of said belts and thereby support the board when the latter is swung forwardly to a horizontal position, said belts yielding with the yield of said pulleys under the weight of said board to allow the latter to assume a substantially horizontal position, and said brackets having grooves for the reception of the engaging means on said belts.

17. The combination with a rotary platen, of a work-sheet-supporting board pivoted to swing about the platen axis, yieldingly supported pulleys at the upper portion of said board, endless belts connecting the platen ends and said pulleys, said belts having work-sheet engaging means, a platen frame, brackets upon said frame having curved surfaces to engage the forward spans of said belts and thereby support the board when the latter is swung forwardly to a horizontal position, said belts yielding with the yield of said pulleys under the weight of said board to allow the latter to assume a substantially horizontal position, and means for automatically locking said board in its horizontal position.

18. The combination with a rotary platen and a paper table, of a work-sheet-supporting board pivoted to swing about the platen axis, a rear frame secured to the paper table, said work-sheet-supporting board and rear frame having angles which coincide when said supporting board is swung back to operative position, and means on said rear frame for limiting the backward movement of said supporting board, to provide a

clearance therebetween, the angles of said supporting board allowing it to lie substantially horizontally when swung forwardly for sheet assembling purposes.

19. The combination with a rotary platen and a paper table, of a work-sheet-supporting board composed of a skeleton frame pivoted to swing about the platen axis, a rear skeleton frame secured to the paper table and having a continuous sheet covering its forward surface; said work-sheet-supporting board and said rear frame with its surface sheet having angles which coincide when said supporting board is swung back to operative position, and means on said rear frame for limiting the backward movement of said supporting board to provide a clearance therebetween, the angles of said supporting board allowing it to lie substantially horizontally when swung forwardly for sheet assembling purposes.

20. The combination with a typewriting machine having a rotary platen and a frame therefor, of a work-sheet-supporting board to swing about the platen axis, yieldingly supported endless carriers upon said board, a rod journaled transversely upon said board and having a terminal crank arm, and a catch mounted upon the platen frame and having a cam arranged in the path of said crank arm, to engage therewith as said board is swung forwardly to a horizontal position, to lock said board in that position.

21. A sheet-collating device for typewriting machines, comprising a collating board shiftable forwardly from an upright operative position to a horizontal sheet-assembling position; sheet-advancing carrier members on said board; a stationary member for supporting said board in operative position, located at the rear thereof; and supporting members individual to said carrier members and directly engageable with the same when said board is in sheet-assembling position.

22. A sheet-collating device for typewriting machines, comprising a collating board shiftable forwardly from an upright operative position to a horizontal sheet-assembling position; sheet-advancing carrier members on said board provided with sheet-engaging devices; and supporting members individual to said carrier members and directly engageable with the same when said board is in sheet-assembling position, said supporting members having grooves for the reception of said sheet-engaging devices.

23. A sheet-collating device for typewriting machines, comprising a collating board shiftable forwardly from an upright operative position to a horizontal sheet-assembling position; sheet-advancing carrier members on said board provided with sheet-engaging devices; a stationary member for supporting said board in operative position; and supporting members individual to said

carrier members and directly engageable with the same when said board is in sheet-assembling position, said supporting members having grooves for the reception of said sheet-engaging devices:

24. A sheet-collating device for typewriting machines, comprising a collating board shiftable forwardly from an upright operative position to a horizontal sheet-assembling position; a sheet-advancing carrier on said board provided with two spaced rows of sheet-engaging devices; and a pair of supporting members directly engageable with said carrier when said board is in sheet-assembling position, each supporting member having a groove for the reception of the adjacent row of sheet-engaging devices.

25. A sheet-collating device for typewriting machines; comprising a collating board shiftable forwardly from an upright operative position to a horizontal sheet-assembling position; a sheet-advancing carrier on said board provided with two spaced rows of sheet-engaging devices; a stationary member for supporting said board in operative position, located at the rear thereof; and a pair of supporting members directly engageable with said carrier when said board is in sheet-assembling position, each supporting member having a groove for the reception of the adjacent row of sheet-engaging devices.

26. A sheet-collating device for typewriting machines, comprising a collating board shiftable forwardly from an upright operative position to a horizontal sheet-assembling position; endless sheet-advancing belts carried by said board; and brackets individual to said belts, having curved surfaces to engage the forward stretches thereof and thereby support the board when the latter is in sheet-assembling position.

27. A sheet-collating device for typewriting machines, comprising a collating board shiftable forwardly from an upright operative position to a horizontal sheet-assembling position; endless belts carried by said board and provided with sheet-engaging devices; and supporting brackets individual to said belts and directly engageable with the forward stretches thereof when said board is in sheet-assembling position, said brackets having grooves for the reception of said sheet-engaging devices.

28. A sheet-collating device for typewriting machines, comprising a collating board shiftable forwardly from an upright operative position to a horizontal sheet-assembling position; endless belts carried by said board and provided with sheet-engaging devices; and brackets individual to said belts, having curved surfaces to engage the forward stretches thereof and thereby support said board when the latter is in sheet-assembling position, said brackets being grooved to receive said sheet-engaging devices.

29. The combination, with a rotary platen, and its axle; of a sheet-collating board pivoted to swing forwardly about said axle from an upright operative position to a sheet-assembling position, said board having an angular construction which enables its forward portion to lie substantially horizontally when swung into sheet-assembling position, means for supporting said board in such position; and a stationary member for supporting said board in operative position.

30. The combination, with a rotary platen, and its axle; of a sheet-collating board provided at its lower end with forwardly extending lugs which are pivoted to said axle, to enable said board to swing forwardly about said axle from an upright operative position to a sheet-assembling position, said board being offset at its junction with said lugs and having its lower portion extending from said junction at such an angle to its upper portion that in the operative position of the board, the first-named portion is given a rearward inclination with relation to the second-named portion, and that in the sheet-assembling position thereof, said second-named portion is enabled to lie substantially horizontally.

31. The combination, with a rotary platen, and its axle; of a sheet-collating board provided at its lower end with forwardly extending lugs which are pivoted to said axle, to enable said board to swing forwardly about said axle from an upright operative position to a sheet-assembling position, said board being offset at its junction with said lugs and having its lower portion extending from said junction at such an angle to its upper portion that in the operative position of the board, the first-named portion is given a rearward inclination with relation to the second-named portion, and that in the sheet-assembling position thereof, said second-named portion is enabled to lie substantially horizontally; means disposed forward of said platen for supporting said board in sheet-assembling position; and a stationary member disposed behind said platen for supporting said board in operative position.

32. The combination, with a rotary platen; of a sheet-collating board pivoted to swing forwardly about the platen axis from operative position to sheet-assembling position; and means operative automatically to lock said board against movement on reaching the second-named position.

33. The combination, with a rotary platen; of a sheet-collating board pivoted to swing forwardly about the platen axis from operative position to sheet-assembling position; separate devices for supporting said board

in both positions; and means operative automatically to lock said board against movement on reaching the second-named position.

5 34. The combination, with a rotary platen; of a sheet-collating board pivoted to swing forwardly about the platen axis from operative position to sheet-assembling position; a spring-controlled element carried by said board; and a catch engageable automatically with said element when the board reaches the second-named position, to lock said board in such position.

10 35. The combination, with a rotary platen; of a sheet-collating board pivoted to swing forwardly about the platen axis from operative position to sheet-assembling position; a spring-controlled rocking rod carried by

said board; and a catch engageable automatically with said rod when the board reaches the second-named position, to lock said board in such position.

15 36. The combination, with a rotary platen; of a sheet-collating board pivoted to swing forwardly about the platen axis from operative position to sheet-assembling position; a spring-controlled rod carried by said board and provided with a terminal crank arm; and a catch engageable directly with said arm when the board is swung into the second-named position, to lock said board in such position.
